ROTATABL E BOLT FOR SUBMACHINE GUNS

Harry A. Asby, Jr., Grosse Pointe, Mich.

Application October 24, 1947, Serial No. 781,860

1 Claim. (Cl. 89—172)

(Granted under Title 35, U. S. Code (1952),
sec. 266)

1

This invention relates to an automatic firearm of the light submachine gun type and more particularly to improvements therein.

Most automatic firearms of the submachine gun type are somewhat cumbersome and heavy to handle due largely to the design of the weapon and particularly where the blow-back principle is utilized in such firearms. It is well known that such principle requires an inertia member of large mass to resist the recoil forces. While such weapons generally are relatively inexpensive to manufacture, the comparatively great weight thereof makes them exceedingly awkward to handle and reduces the useful load that the soldier may carry with him thereby limiting the usefulness of such a firearm.

Accordingly it is an object of this invention to provide an automatic firearm of light weight which can be readily and easily handled.

Another object of this invention is to provide a firearm of the automatic type wherein the breech elements are contained within a unitary housing.

Still another object of this invention is to provide improved barrel guiding and barrel return means for a firearm having a recoiling barrel.

The specific nature of the invention as well as other objects and advantages thereof will clearly appear from a description of a preferred embodiment as shown in the accompanying drawings in which:

Fig. 1 is a side elevational view of the firearm.

Fig. 2 is a longitudinal sectional view of the firearm illustrated in Fig. 1 and shown in battery position, prior to release of the hammer.

Fig. 3 is a view similar to Fig. 2 showing the hammer in the forward position prior to the start of the recoil movement of the bolt and related components.

Fig. 4 is a view similar to Fig. 2 showing the barrel returned to its initial position by the bias of the barrel return spring.

Fig. 5 is a view similar to Fig. 2 showing the bolt and bolt cam at the rearmost position of recoil movement.

Fig. 6 is a cross sectional view taken along line 6—6 of Fig. 2.

Fig. 7 is a detail fragmentary view showing the bolt handle cam and bolt handle slot in the sleeve.

Fig. 8 is a fragmentary cross sectional view taken along the line 8—8 of Fig. 1.

Fig. 9 is an enlarged detail view showing the manner of securing the bolt handle to the bolt.

Fig. 10 is a detail top view of the cover utilized to close the ejection port on the sleeve.

Fig. 11 is a detail view of the front plug and

2

latching means for locking such plug to the sleeve.

Fig. 12 is a detail view of the bolt, bolt cam, recoil spring and recoil plug shown in the locked battery position.

5 Fig. 13 is a similar view but showing the bolt prior to rotation to the locked position by the cam.

Fig. 14 is a cross sectional view taken along the line 14—14 of Fig. 5.

10 Fig. 15 is an enlarged detail view in longitudinal section showing the barrel guide means and barrel return spring mounted at the forward end of the sleeve.

Fig. 16 is a detail view of the receiver showing the magazine well and ejection port therein.

Fig. 17 is a longitudinal sectional view of Fig. 16.

Fig. 18 is a cross sectional view taken along the line 18—18 of Fig. 17.

Fig. 19 is a cross sectional view taken along the line 19—19 of Fig. 17.

Fig. 20 is an enlarged longitudinal sectional view of the firing mechanism.

Fig. 21 is an enlarged top view of the secondary sear assembled to the rib of the trigger guard housing.

Fig. 22 is a side elevational view of Fig. 21.

Fig. 23 is a fragmentary longitudinal cross-sectional view of the bolt.

Fig. 24 is a longitudinal cross-sectional view 30 of the bolt cam.

The firearm to be presently described in greater detail is recoil operated, and is positively locked at the moment of discharge of the cartridge. The barrel and receiver of such firearm are slidably contained within a tubular sleeve and such members recoil approximately $\frac{3}{8}$ of an inch upon discharge of a cartridge to effect unlocking of the bolt from the receiver. The residual gas pressure then forces the bolt to the end of its recoil stroke whereupon a recoil spring returns the bolt to battery position. A cam member adjacent the rear of the bolt effects rotation of such bolt to the locked position. A cover is provided on the firearm to shield against the entry of dirt into the breech mechanism when such firearm is not being fired. Means on such cover is utilized to block the fire control mechanism so that the firearm can not be discharged unless such cover is opened.

50 There is shown in Fig. 4 in assembled relation a firearm of the automatic type. Such firearm comprises a tubular sleeve 1 containing the major elements of the firearm namely, a barrel 2, a receiver 3, and a bolt 4. A trigger guard housing 5 is secured to the underside of the firearm in a

manner as will be described, such housing containing the fire control mechanism. A magazine well 6 is secured to the underside of sleeve 1 immediately ahead of trigger guard housing 5 and is adapted to receive a cartridge magazine 7.

Sleeve 1 is a long tubular member and is provided to house the breech elements of the firearm as mentioned above. The forward end of sleeve 1 is of an enlarged diameter as shown at 8 in Figs. 2, 3, 4, and 15, for a reason to be presently described.

Receiver 3 (Figs. 16, 17, 18 and 19) is a cylindrical member and is provided with an axial bore 9 and the forward end thereof is counterbored and threads 10 are provided therein. A cartridge ejection port 11 is provided on top of receiver 3 to permit the fired cartridge cases to be ejected therethrough. An opening 12 is provided on the underside of receiver 3 in alignment with magazine well 6 in order that a cartridge may be fed from magazine 7 into the barrel chamber. A transverse notch 13 is provided in receiver 3 at the rear end of ejection port 11 to admit a locking lug as will be later explained. Such notch is formed on a suitable helix and a locking surface 14 is thereby provided against which the bolt 4 is locked as will be later described. A longitudinally disposed spline 15 is provided on the inside of receiver 3 to permit movement of the extractor 41.

Receiver 3 is secured to barrel 2 by threads 10 and such assembly is slidably contained within sleeve 1 for limited longitudinal reciprocal movement therein. That portion of barrel 2 which lies within the large diameter 8 of sleeve 1 (Fig. 15) is of reduced diameter as shown at 16 and a shoulder 17 is formed by such reduced diameter. The portion 16 of barrel 2 extends forwardly a short distance whereupon the barrel is still further reduced in diameter and a threaded portion 18 is provided thereon.

A cup-like gland 19 surrounds reduced diameter 16 of barrel 2 and abuts the rear end of enlarged diameter 8 of sleeve 1. A barrel guide 20 is screwed onto threaded portion 18. A barrel return spring 21 surrounds reduced diameter portion 16 of barrel 2 between cup-like gland 19 and the rear face of barrel guide 20. Such spring is provided to bias barrel 2 forwardly as will be later described. Barrel guide 20 provides a front bearing for barrel 2 so that such barrel will be properly aligned within sleeve 1 and yet be slidably mounted therein. Suitable detent means such as a split ring spring 22 is provided to prevent rotation of barrel guide 20 when such guide is properly adjusted. A plug 23 is screwed into the forward open end of sleeve 1 and is provided to arrest the forward movement of barrel 2 within sleeve 1. A spring biased latch 25 on plug 23 engages a plurality of notches 24 provided on the front end of sleeve 1 to secure plug 23 against rotation.

Latch 25 essentially comprises a rectangular member, and a plurality of serrations 27 corresponding to notches 24 are provided on one end thereof. Latch 25 is contained within a suitable slot on plug 23 so that serrations 27 on the end thereof engage notches 24. Plug 23 is counterbored as shown at 28 in Figs. 11 and 15 and a semi-circular spring 29 is secured to the bottom of such counterbore by rivets 30. A tang 31 is provided on spring 29 which is secured to rectangular latch member 25 by rivets 32. Thus latch 25 is held in engagement with notches 24 by spring 29. Such latch may be readily disen-

gaged from such notches by sliding latch 25 forwardly away from notches 24. The outer surface of latch 25 is serrated to facilitate such movement.

Bolt 4 (Figs. 2, 12 and 13) is a cylindrical member provided with an enlarged diameter rear end portion 26. An axial hole 33 is provided in bolt 4 which is of suitable configuration to receive a firing pin 34. An enlarged head portion 35 is provided on firing pin 34 which is contained within a counterbored portion 36 of hole 33. A helical spring 37 surrounds firing pin 34 and such spring abuts the head 35 of firing pin 34 and the bottom of counterbored portion 36, such spring being provided to bias firing pin 34 rearwardly so that the point thereof can not accidentally strike the primer of a cartridge. A transverse pin 38 in bolt 4 engages a transverse notch 39 on the forward end of firing pin 34 to secure such firing pin to the bolt and to permit limited longitudinal movement thereof.

A longitudinal slot 40 is provided on the forward end of bolt 4 in which is placed an extractor 41. Such extractor is pivoted therein by a transverse pin 42. A spring 43 placed under the rear end of extractor 41 biases the forward end of such extractor into engagement with the rim of a cartridge. A longitudinally disposed locking lug 44 is provided on bolt 4 which engages locking surface 14 on receiver 3. A suitable ejector (not shown) is contained in the face of the bolt. The rear end portion 26 of bolt 4 is counterbored and a cam 45 is provided in such portion, being disposed as shown in Figs. 12 and 13. On the forward end of portion 26 (Fig. 9) a radially disposed threaded hole 47 is provided to receive a bolt handle 48 to be later described.

A bolt cam 49 (Figs. 2, 3, 4, 5 and 13) is slidably contained within sleeve 1 adjacent the rear end of bolt 4. Such cam is a cylindrical member having a forwardly projecting end 50 which is provided with a cam surface 51. Such cam surface cooperates with cam 46 to rotate bolt 4 to a locked position as will be later described. A longitudinal groove 131 (Fig. 5) is provided on the bottom of bolt cam 49 which is engaged by a rib 132 on trigger guard housing 5 to maintain such cam in one position. The cylindrical body portion of bolt cam 49 is counterbored and one end of a recoil spring 52 is inserted therein. The other end of spring 52 is retained within sleeve 1 by a recoil plug 53. Such plug is secured to the end of sleeve 1 by threads 54. Plug 53 is secured against rotation in a manner similar to that for securing the front plug 23. An integral axially disposed spring guide 55 is provided on plug 53 which supports spring 52 contained within sleeve 1 and also arrests the rearward movement of bolt cam 49. A plurality of discs 56, preferably of fiber, are secured to the bottom of the counterbored end of bolt cam 49 to cushion the shock of the recoiling members at the end of the recoil stroke, as shown in Fig. 5.

To prevent receiver 3 and likewise barrel 2 from rotating within sleeve 1, a longitudinal slot 57 (Fig. 17) is provided on the bottom of receiver 3 near the rear end thereof. Such slot is engaged by a vertically disposed pin 58 mounted in the forward end of trigger guard housing 5. Trigger guard housing 5 (Figs. 4 and 6) is of built-up construction and comprises a trigger guard 69, a pistol grip 60 and side plates 61 and 62. These elements are preferably brazed to form a unitary structure. At the rear end of

housing 5, there is provided a tang-like end 63. Such end rests within a recess 64 formed by a strap 65 welded to the underside of sleeve 1. The forward end of housing 5 is secured to a depending lug 130 by a transverse headed pin 66 as shown in Figs. 5, 6, and 8. Lug 130 is preferably secured to the underside of sleeve 1 by welding and abuts the rear surface of magazine well 6. A suitable spring detent 61 is provided to secure pin 66 against displacement. Trigger guard housing 5 is readily disassembled from sleeve 1 by removing pin 66 so that the front end of such housing can be dropped away from sleeve 1 whereupon tang 63 can be readily removed from recess 64.

A hammer 68 (Figs. 2, 3, 4 and 5) of substantially triangular construction is pivotally mounted within trigger guard housing 5 by a transverse pin 69. A spring biased plunger 70 is arranged as shown in the appended drawings to bias hammer 68 forwardly to strike firing pin 34. A secondary sear notch 71 is provided in the upper rear apex of such hammer. A forwardly projecting lug 82 on hammer 68 integrally formed with the lower apex of such hammer is arranged to be engaged by sear notch 81 when hammer 68 is in the cocked position as will be later shown.

A secondary sear 72 is pivotally mounted on a transverse pin 73 somewhat to the rear of hammer 68. Secondary sear 72 is biased forwardly by a spring 74 so that such sear can engage secondary sear notch 71 on hammer 68. An upwardly projecting lug 75 is provided on secondary sear 72 which projects through a slot 76 provided on the underside of sleeve 1 so that such lug lies in the path of the bolt cam 89 for a purpose to be later described. Slot 76 is of sufficient length to permit hammer 68 to rotate upwardly into sleeve 1 to strike firing pin 34.

A trigger 77 and a safety latch 78 are mounted on a transverse pin 79 in trigger guard 59. Trigger 77 is provided with an upwardly projecting lug 80. Such lug is provided with a transverse sear notch 81. A spring 83 is provided in back of trigger 77 to bias such trigger forwardly so that sear notch 81 will engage hammer 68 upon release of such trigger. A substantially horizontal lug 84 is provided on trigger 77 which strikes a portion 85 of trigger guard housing 5 to limit the forward pivotal movement of trigger 77.

Safety latch 78 is a substantially L-shaped member, the lower portion of such member however is arcuately formed as shown at 86 and rests within slot 82 in trigger guard 59 to permit limited pivotal movement of latch 78. A spring 87 is placed between the arcuately formed portion 86 of latch 78 and portion 85 of trigger guard housing 5. Such spring is provided to bias the upright portion of latch 78 forwardly into engagement with a stud 88 mounted on a cover 89 as will be later described. A forwardly facing lug 90 is provided on latch 78 which rests on a horizontal shelf 91 provided on trigger guard housing 5 to limit the forward movement of the upright portion of latch 78.

A vertically disposed recess 93 is provided on the underside of trigger guard housing 5 on the forward end thereof. A magazine latch 94 is pivotally mounted therein by a transverse pin 95. Such latch comprises a vertical arm 97 and a horizontal arm 98 and spring 96 is provided in the rear of arm 97 to bias such latch forwardly. The end of arm 98 rests on top of a shelf 91 of portion 85 to secure the rear end of such latch thereon.

An integral projection 99 is provided on the lower forward face of latch 94. Such projection is arranged to engage a corresponding lug 100 provided on magazine 7 to secure such magazine within magazine well 6. Projection 99 is readily rotated out of the path of lug 100 by pivoting latch 94 about pin 95 against the bias of spring 96 in a clockwise direction. This permits magazine 7 to drop out of magazine well 6. The insertion of a loaded magazine into magazine well 6 cams projection 99 of latch 94 out of the path thereof until such projection is in back of lug 100, whereupon spring 96 biases latch 94 in a counterclockwise direction so that projection 99 engages lug 100.

Cover 89 is of suitable arcuate shape to surround the ejection port 11 of receiver 3 and the corresponding opening 101 in sleeve 1. Such cover is pivotally secured to sleeve 1 by a hinge 102. A hinge pin 103 is provided to secure the cover to hinge 102 and a torsion spring 104 surrounds pin 103. Spring 104 is mounted in such fashion on pin 103 and secured to cover 89 so as to normally maintain such cover in the open position. An integral downwardly projecting tab 105 is provided near the rear edge of cover 89 and stud 88 is secured to such tab preferably by a collar 106. In the closed position of cover 89 (Fig. 6), stud 88 assumes a substantially horizontal position. The inwardly projecting end of stud 88 is conically shaped as shown at 107 and a transverse slot 108 is provided on stud 88 which is engaged by safety latch 78 as will be presently described. A notch 109 (Fig. 1) is provided in cover 89 to permit such cover to clear bolt handle 48 when cover 89 is closed. Such notch likewise prevents bolt handle 48 from being retracted thereby providing a further safety feature.

When cover 89 is closed against the bias of spring 104, the conically shaped end 107 of stud 88 contacts the upright arm of latch 78 thereby rotating such latch slightly in a counterclockwise direction until slot 108 in stud 88 is aligned with the upright member of latch 78. Spring 87 then biases the upright arm of latch 78 in a clockwise direction so that such arm will engage slot 108. Thus cover 89 is secured in a closed position. When in the closed position, the conically shaped end 107 of stud 88 contacts the forward end of lug 80 of trigger 77. Thus trigger 77 can not be pulled rearwardly to disengage hammer 68 from sear notch 81 on trigger 77. Thus there is provided a simple and positive method of securing the fire control mechanism in a safe position.

Bolt handle 48 (Figs. 6, 7, and 9) is a short cylindrical member and is provided with an end 110 of reduced diameter. Such end is threaded and is screwed into threaded hole 47 in bolt 4. A cam surface 111 is provided on the portion of bolt handle 48 adjacent threaded end 110 for a purpose to be presently described. A cylindrical recess 112 is provided in the other end of bolt handle 48 and a longitudinal slot 113 is provided in the wall of bolt handle 48 which communicates with recess 112 and extends substantially the full length of bolt handle 48. A latch 114 is pivotally mounted within slot 113 by a transverse pin 115. A split ring spring 116 is placed within an annular groove 117 provided on bolt handle 48. Such spring likewise passes over latch 114 and is provided to bias the lower end of latch 114 into a slot 118 in bolt 4 when such bolt handle is assembled to bolt 4. Spring 116 likewise biases the upper end of latch 114 into cylin-

drical recess 112. To pivot the lower end of latch 114 out of slot 118 in order to unscrew bolt handle 48 from bolt 4, a cartridge 119 may be inserted into cylindrical recess 112 and forced downwardly therein against the sloped upper end of latch 114 thereby forcing such latch outwardly through slot 113 and forcing the lower end of such latch out of slot 118 thereby unlocking bolt handle 48 so that such handle may be readily disassembled.

Cam surface 111 on bolt handle 48 cooperates with a corresponding cam surface 120 on sleeve 1 which effects unlocking of locking lug 44 on bolt 4 from locking surface 14 of receiver 3 whereupon bolt handle 48 travels rearwardly along a longitudinal slot 121 provided in sleeve 1.

A forearm 122, preferably of wood, is secured to the underside of sleeve 1 (Fig. 3) by a vertically disposed screw 123 which is threaded into a boss 124 provided on the underside of sleeve 1. A front sight 125 is secured to the muzzle end of barrel 2 by any conventional means. A rear sight 126 is secured to the top of sleeve 1 near the rear end thereof by screws 127. Such sight may be any conventional type of sight utilized on small arms but is preferably of the construction as shown on the appended drawings wherein an upright member 128 is integrally formed at right angles to a suitable base, and a sighting aperture 129 is provided in the upright member.

Operation

The firearm illustrated in the appended drawings is charged by inserting a loaded magazine 7 into magazine well 6. Magazine latch 94 engages lug 100 on magazine 7 to secure such magazine to the firearm. Cover 89 is released by pushing forwardly on safety latch 78 which rotates the upwardly projecting arm in a counter-clockwise direction and out of slot 108 in stud 88. Torsion spring 104 then biases cover 89 about hinge 102 to the open position, thus uncovering ejection port 11 and removing that portion of cover 89 surrounding bolt handle 48. The firearm may now be charged by retracting bolt handle 48 rearwardly. Manual retraction of bolt handle 48 moves the breech elements rearwardly a distance of approximately $\frac{3}{8}$ of an inch whereupon barrel guide 20 strikes the forward end of gland 19.

During the course of this movement, cam surface 111 of bolt handle 48 travels along cam surface 120 provided on sleeve 1. The cooperation of these two cam surfaces rotates bolt handle 48 in a clockwise direction as shown in Fig. 6, thereby effecting unlocking of locking lug 44 from locking surface 14. Upon unlocking of bolt 4, barrel return spring 21 biases receiver 3 and barrel 2 forwardly to the normal forward position. Continued rearward movement of bolt 4 forces hammer 68 to be rotated in a counterclockwise direction whereupon such hammer is engaged by sear notch 81 of trigger 77. Driving spring 52 returns bolt 4 and bolt cam 49 to the battery position upon release of bolt handle 48. Cam surface 51 provided on bolt cam 49 engages cam 46 provided on the rear end of bolt 4, thereby rotating such bolt to the locked position by rotation of lug 44 into engagement with locking surface 14 provided on receiver 3.

The firearm is now charged and a cartridge is chambered in the barrel. Release of hammer 68 is effected when trigger 77 is pulled rearwardly, rotating lug 80 in a clockwise direction which engages sear notch 81 from lug 82 of hammer 68.

Spring biased plunger 70 then forces hammer 68 in a clockwise direction to strike firing pin 34 whereupon the cartridge is discharged. The recoil force resulting from the discharge of the cartridge forces barrel 2, receiver 3, and bolt 4 contained within receiver 3, to move rearwardly approximately $\frac{3}{8}$ of an inch whereupon unlocking of bolt 4 is effected as above described.

Hammer 68 is again rotated in a counterclockwise direction, but as trigger 77 is still held rearwardly, sear notch 81 is held out of engagement with lug 82 on hammer 68. However, secondary sear 72 is biased outwardly by spring 74 whereby secondary sear notch 71 provided on hammer 68 is engaged by secondary sear 72. Hammer 68 is thus held momentarily in the cocked position until bolt 4 is returned to its locked battery position by spring 52. Immediately after locking of bolt 4, bolt cam 49 strikes the upwardly projecting lug 75 of secondary sear 72 thereby rotating such sear in a clockwise direction. Such rotation causes secondary sear 72 to slip out of engagement with sear notch 71 on hammer 68. Thus hammer 68 is free to be biased forwardly by plunger 70 to strike firing pin 34.

It is desired to point out that the fire control mechanism herein described is for full automatic operation only. Accordingly such firearm can only be fired in bursts of short duration or long continuous bursts. Release of trigger 77 at any time during firing permits sear notch 81 to re-engage lug 82 of hammer 68 to hold such hammer in the cocked position.

Disassembly

The firearm herein described is readily broken down into major assemblies for ease in cleaning, or to permit repair of damaged or broken parts. Trigger guard housing 5 is readily removed by forcing pin 66 outwardly whereupon the front end of such trigger guard housing may be pulled downwardly. Tang 63 is then readily removed from recess 64. Barrel 2, receiver 3 with the bolt mounted therein, and the bolt cam may then be readily removed by removal of front plug 23. Removal of such plug was previously described. The components just mentioned, along with the barrel guide 20 and gland 19 with barrel return spring mounted therein, can be readily removed from the muzzle end of the sleeve 1. Removal of recoil plug 53 and spring 52 permits free access to the interior of sleeve 1 for cleaning and oiling.

From the foregoing description it is readily apparent that there is here provided a light, sturdy constructed firearm that is positive in operation and one that can be readily and cheaply fabricated. This firearm is provided with a positive fire control mechanism for automatic fire and has positive safety features whereby the trigger is securely blocked to prevent accidental discharge of the firearm. Further, this firearm is positively locked at the moment of discharge of a cartridge and remains so for an appreciable length of time to permit safe unlocking at a substantially reduced breech pressure.

It is to be understood that the form of my invention, herewith shown and described, is to be taken as a preferred example of the same, and that various changes in the shape, size and arrangement of parts may be resorted to, without departing from the spirit of my invention, or the scope of the subjoined claim.

I claim:

In an automatic firearm, a fixed outer sleeve having a longitudinal slot terminating at its for-

ward end in an enlarged cam portion, a barrel slidably mounted in said sleeve for limited recoil movement, a receiver fixedly secured to said barrel for movement therewith in said sleeve, said receiver having an axial bore therethrough, a bolt reciprocably mounted in said axial bore, said receiver including a rearwardly-disposed, uninterrupted, circumferential portion having a first cross sectional area, a further portion having a reduced cross sectional area immediately adjacent the forward end of said uninterrupted circumferential portion and forming a locking stop shoulder, and a transitional, helical locking surface between said reduced cross sectional area and said first-mentioned cross sectional area, a locking lug projecting from the side of said bolt in cooperative relationship with said reduced bore area and said helical locking surface to lock said bolt in battery position, an operating handle secured to said bolt rearwardly of said locking lug and said uninterrupted circumferential portion and extending through said longitudinal slot in said sleeve, a cam surface on said operating handle cooperating with said enlarged cam portion in said slot of said sleeve during recoil of said receiver to rotate said bolt in one direction for

disengaging said locking lug from said helical locking surface in said receiver, and single cam means for rotating said bolt in the opposite direction at the conclusion of counterrecoil movement for completely re-engaging said locking lug with said helical cam surface to lock said bolt in battery position.

HARRY A. ASBY, JR.
